MUCKING MACHINE FOR USE IN SHAFT SINKING

Francis Tofflemire, Thermopolis, Wyo.

Application November 9, 1955, Serial No. 545,911

2 Claims. (Cl. 214—141)

This invention relates to mucking machines for mine shafts.

An object of the invention is the provision of an improved mucking machine particularly adapted to operate in the restricted space of a vertical or nearly vertical mining shaft or similar type excavation.

Another object of the invention is to provide a mucking machine which combines an extensible shovel or scoop supporting boom with improved means for controlling or operating the shovel for maximum mucking efficiency.

Another object of the invention is the provision of a mucking machine for use in mines of the type having a relatively narrow shaft and a space of greater area than said shaft at the bottom thereof, the machine being adapted to readily muck material from all points at the bottom yet being easily collapsed to permit quick withdrawal of the machine from the shaft during periods of blasting, or for other reasons.

Other objects and their attendant advantages will become apparent as the following detailed description is read in conjunction with the accompanying drawings wherein:

Fig. 1 is a vertical section showing the apparatus of the invention applied to mucking operations at the bottom of a mine shaft, the dotted lines indicating certain alternative positions of the apparatus, and

Fig. 2 is a front elevation of the apparatus of Fig. 1.

Referring now to Fig. 1 there is shown at 10 a substantially vertical mine shaft which is illustrated as having a relatively narrow upper part 12 and an enlarged excavated lower part 14 from which broken rock or ore is to be removed.

The mucking machine of the invention comprises a cage or cab 16 mounted for transverse movement on traversing rails 18 secured in any known manner to one wall of the mine shaft. The rails 18, for example, may be I-shaped beams whose channeled upper surfaces are engaged by suitable L or T-shaped members 20 fixed to the one vertical wall of the cage 16. The cage is moved transversely by any suitable means as by hydraulically operated thrust rods indicated generally by the number 22.

The cage 16 is of frame construction having at the top an eye 24 engageable by hoisting means (not shown) by which the cage and associated mechanism is raised or lowered in the shaft. The cage 16 includes an operator's seat 26 next to which are controls 28 and beneath which may be located a power unit 30 which includes a hydraulic pump unit 31. Secured to the front of the cage is the mucking boom 32 and associated mechanisms, described more particularly hereinafter, and secured to the end of the boom is the mucking shovel 34.

As illustrated in Fig. 2, the boom 32 may for purposes of strength be constructed of two identical side-by-side members which are pivotally connected at their inner ends to brackets 36 secured to the lower end of a vertical member 38 which is pivotally supported at 39, 40 to the front of the cage frame 16 for horizontal swinging movement. The vertical member 38 has pivotally

2

secured to its upper end at 42 one end of a pair of hydraulic power cylinders 44 each containing a double acting piston 46 having a piston rod 48 pivotally attached at 49 to an intermediate portion of each of boom members 32. When fluid pressure is admitted to the lower ends of the power cylinders 44 the pistons 46 are moved upwardly to raise the boom members 32 and when pressure is admitted to the upper ends of the power cylinder the boom members are lowered.

10 In accordance with the invention the boom members 32 are extensible in order that the shovel 34 may be thrust into remote corners of the mine shaft. This extensibility is accomplished by constructing the boom 32 telescopically with outer portions 50 serving as power cylinders for inner portions 51 having pistons 52 integral with their inner ends which serve to extend or retract the boom as fluid pressure is admitted to one end or the other of the cylinder portions 50.

The outer ends of the inner boom members 51 are offset as at 53 and at their outer ends pivotally support the upper end of a pair of opposed shackle members 54 by means of a suitable bolt or the like 55 which extends through registering holes in the shackle ends and in each of the offset portions 53 of the boom so that the pair 25 of booms thus joined act essentially as a unitary member.

As illustrated in Fig. 2 the lower ends of shackle members 54 pivotally support the shovel 34 which is moved with respect to the shackle between opened and closed positions by hydraulic power actuators, the cylinders 56 30 of which are pivotally connected to the upper ends of the shackles 54 and the pistons 57 of which are connected to the shovel through the medium of offset piston rods 58. As the pistons 57 are moved inwardly or outwardly the shovel is tilted with respect to the boom-end to the various 35 dotted line positions shown in Fig. 1.

In order that the shovel can be extended if necessary beyond the normal reach of the fully extended boom the invention provides a novel means for automatically swinging the shackles 54 outwardly and this means comprises 40 a flexible member 59 whose inner end is attached to the outer or cylinder portion 50 of the boom while its inner end is attached to a lever 60 which may be fixed to the shackle normal to the axis thereof by being welded to a suitable cross brace 61, shown in Fig. 2, joining the two sides of the shackle. As illustrated in Fig. 1, when 45 the boom 32 is in its fully extended position, the flexible member exerts a counter-clockwise pull on the lever 60 causing the shackle to rotate counter-clockwise to a position substantially parallel to the boom 32 as indicated by the dotted lines in Fig. 1. With the shackle thus extended 50 the reach of the shovel is lengthened by the length of the shackle and the shovel may, as before, be rotated with respect to the shackle by the shovel power actuators.

The bucket is moved across the floor of the mine to collect material therein by means of an over haul cable 55 62 having one end fixed to the cab 16. The cable passes around a sheave 63 fixed to the bucket 34 thence around a second sheave 64 fixed to the cab which guides the cable to a winding and unwinding drum 66 rotatably mounted on the lower portion of the cab framework. The 60 drum is rotated in a conventional manner by means of belts and gearing 67 driven by the power unit 30 and its movement and direction of rotation is determined by the positioning of conventional clutches controlled by the operator from the control station 28.

65 As is customary in the mucking of mine shafts, loosened material on the mine floor is deposited in a sinking bucket for lifting to the surface. In order that the sinking bucket may be filled in its position of rest on the mine floor it is necessary that the mucking shovel boom be 70 movable horizontally and this is accomplished in the present invention by a power cylinder 68 pivotally fixed

at its inner end to the cab and containing a piston 69 whose rod 70 is pivoted to the outer end of a transverse projection 71 fixed to the hinged vertical member 38 carrying the boom 32. As the piston is extended or retracted the hinged member and the boom will be swung transversely in accordance with the direction of movement of the piston.

In operation, the rails 18 are positioned and secured in the shaft 12 and the cab 16 is mounted thereon. The power unit 30 is energized to operate the hydraulic pump unit 31 to build hydraulic pressure in the system. The operator manipulates the controls at 28 to lift the boom 32 by the lifting cylinders and pistons 44, 46. When the shovel 34 is raised clear of the mine floor the operator then swings the boom transversely by the admission of fluid pressure to the proper side of rotating cylinder 68. When the shovel has been swung over the particular portion of the mine floor which is to be mucked the operator extends the boom as necessary by the admission of fluid to the upper side of the boom extension piston 52 and when the boom has been extended sufficiently far the operator then manipulates the controls 28 to admit fluid pressure to the upper side of the shovel control pistons 57 to extend the same and cause the shovel to be tilted until the toothed forward portion thereof is pointing approximately straight downwardly toward the mine floor. The operator may then admit fluid pressure to the upper side of the boom lift pistons 46 to move the boom downwardly and force the teeth of the shovel into the debris to be collected. The clutch of the winding drum 66 is then engaged to wind in the overhaul cable 62 and draw the shovel towards the wall of the shaft until the shovel is loaded. The drum clutch is then released and the shovel pivoted upwardly by the admission of fluid pressure to the lower side of the shovel control pistons 57. The boom 32 is raised and swung horizontally until the shovel is over the sinking bucket whereupon the shovel is pivoted downwardly discharging its contents into the sinking bucket. This process is repeated until the sinking bucket is loaded and by alternating the successive position of the sinking bucket with transverse movements of the mucker from side to side of the shaft on the rails 18 all of the loose debris can be cleared from the shaft bottom. For debris in remote corners of an excavated portion of the mine the reach of the shovel is extended as necessary by merely extending the boom until the flexible member 59 acts on the lever 60 to rotate the shackle upwardly about its pivot as indicated by the dotted lines in Fig. 1.

At the completion of the clearing operation in the shaft hoisting equipment is attached to the hoist cage eye 24 and the cab 16 is raised clear of the rails 18. As the cab rises the lift pistons 46 are extended so that the

boom, shackle and shovel hang suspended allowing movement of the mucking equipment through the very limited space available in a conventional mining shaft. The equipment is raised sufficiently far in the shaft to a point above danger of blast damage where it may be held until the completion of blasting operations before being again lowered to the rails 18.

From the foregoing description it will be apparent that the mucking equipment of the present invention is highly versatile and is particularly well adapted for use in mines having shafts of limited cross sectional area. In addition, the ease of mounting the mucker or withdrawing it from the shaft renders the mucker particularly valuable since it eliminates to a large degree the non-productive efforts required heretofore to mount or remove power muckers from mine shafts.

It will of course be apparent that the mucker of the invention is susceptible of many modifications and changes without having departed from the scope of the appended claims.

What is claimed is:

1. In a mucking machine having a telescoping boom, means for extending or retracting said boom, means for swinging said boom in a vertical plane and means for swinging said boom in a horizontal plane, an offset portion integral with the end of said boom, a shackle pivoted to said offset portion and having two spaced arms, a shovel pivoted between said arms, and double acting fluid pressure means interposed between said shackle and said shovel for controllably rotating said shovel about its pivots.
2. In a mucking machine having a telescoping boom, means for extending or retracting said boom, means for swinging said boom in a vertical plane and means for swinging said boom in a horizontal plane, an offset portion integral with the end of said boom, a shackle pivoted to said offset portion and having two spaced arms, a shovel pivoted between said arms, and means for rotating said shackle with respect to said boom to extend the reach thereof, said means comprising a lever fixed to said shackle and projecting outwardly normal to the axis thereof, a flexible member having one end fixed to the outer end of said lever and the other end fixed to a non-telescoping portion of said boom, said flexible member upon extension of said boom acting on said lever to rotate said shackle outwardly about said pivot.
